H. J. FISHER

SIGNALING SYSTEM

Filed Dec. 5, 1923

Inventor:
Harold J. Fisher
by *Edward A. Adams, Atty.*

UNITED STATES PATENT OFFICE.

HAROLD J. FISHER, OF JERSEY CITY, NEW JERSEY, ASSIGNOR TO WESTERN ELECTRIC COMPANY, INCORPORATED, OF NEW YORK, N. Y., A CORPORATION OF NEW YORK.

SIGNALING SYSTEM.

Application filed December 5, 1923. Serial No. 678,662.

To all whom it may concern:

Be it known that I, HAROLD J. FISHER, a citizen of the United States of America, residing at Jersey City, in the county of 5 Hudson and State of New Jersey, have invented certain new and useful Improvements in Signaling Systems, of which the following is a full, clear, concise, and exact description.

10 This invention relates to a signaling system, and more particularly, to an arrangement in which telegraph signals transmitted as a plurality of modulations of a single carrier wave may be received at a 15 distant station substantially free from interference due to random disturbances such as static discharges.

It has heretofore been proposed to provide a radio telegraph system in which a plurality of different frequency waves are used 20 to effect marking signals and a plurality of other waves of different frequencies are used to produce spacing signals.

In the arrangement hitherto proposed a 25 carrier wave is modulated by a current of one frequency to produce a plurality of different carrier frequencies which are used to identify marking signals and the same carrier wave is modulated by a current of 30 different frequency to produce a plurality of other waves of different carrier frequencies which are employed to identify spaces. In both cases the unmodulated carrier component is suppressed. At the 35 receiving station the incoming waves are combined with locally generated oscillations to produce currents of frequencies different from the modulating frequencies, but which correspond thereto. These currents are 40 separately selected and detected or rectified. The currents corresponding to the marking wave trains are each used to energize one winding of a set of windings of a polarized relay and each of the currents corresponding 45 to the spacing wave trains is supplied to one winding of a second set of windings of the polarized relay. The relay is so designed that marking is only effected when 50 all the windings of one set are energized, and spaces are indicated only when all the windings of the other set are energized, whereby the polarized relay is positively actuated in two directions alternately to 55 control the operation of a signal indicator. Static discharges incident upon the antenna

will produce oscillations determined by the natural period of the circuit. These oscillations when combined with the local oscillations will produce current impulses in all of the windings constituting the two sets of 60 windings of the relay, whereby a balanced condition will be produced with reference to the relay armature and hence no effect, due to these impulses, will be produced in the signal indicating circuit. This receiving 65 arrangement, therefore, requires a local oscillator, and also a selective circuit, rectifier, and relay winding for each of the incoming waves, in order that marking and spacing signals may be received and static 70 interference eliminated.

The present invention provides an arrangement in which a carrier wave is modulated by two different frequencies and the modulated and unmodulated components 75 are transmitted to a distant station at which the corresponding components are combined to produce currents of the modulating frequencies which are selected, detected, or rectified and used to energize separate windings of a polarizing relay. In this arrangement the current of one frequency produced by detection is adapted to positively actuate the armature of the relay in one direction 80 to indicate marking signals and similarly the produced current of the other frequency 85 is adapted to positively actuate the armature of the relay in the opposite direction to indicate spaces. Current impulses resulting from static discharges incident upon the 90 antenna, will, in general, be simultaneously supplied to both windings of the polarizing relay and hence will not produce any effect upon the armature of the relay.

In accordance with this invention a controller is adapted to supply the unmodulated and modulated components of a carrier wave modulated with current of one frequency to an antenna and then the unmodulated and modulated components 95 of a carrier wave of the same frequency modulated by a current of a different frequency to the antenna. At the receiving station the first group of carrier and side frequency components are combined in a detector to yield current of the first modulating frequency which is selected, rectified and used to energize one winding 100 of a differential relay and then the second group of carrier and side frequency com- 105 110

ponents are combined in the same detector to yield current of the second modulating frequency which is selected, rectified, and used to energize the other winding of the differential relay. In this manner the relay is positively operated; first in one direction to close a circuit including a marking device and then in the opposite direction to open this circuit to return the marking device to spacing position. Static discharges incident upon the antenna will cause both windings of the relay to be simultaneously and equally energized and no effect due to these impulses will be produced in the indicator circuit.

15 The foregoing is given for the purpose of briefly and in a general way describing one practical embodiment by means of which the objects of this invention may be fulfilled.

One object of this invention is to provide 20 a radio telegraph system embodying a simple arrangement in which the signal impulses are used to positively operate an indicator while impulses due to random interference such as static are neutralized in their 25 effect upon the indicator.

For a complete understanding of this invention reference may be made to the following specification read in conjunction with the attached drawing in which the single 30 figure illustrates a system embodying the invention.

In the drawing there is shown a transmission station T comprising an antenna circuit including a radiating conductor 1, an inductance 2 and an adjustable condenser 3 connected to ground at 4. An arrangement 5 for producing a carrier wave modulated by either one of two different frequency currents, under the control of a key 40 6, is connected to the antenna circuit.

Any well known arrangement for supplying a carrier wave modulated by two currents of different frequencies may be used at the transmission station. By way of example, there is shown a transmission system 45 which is similar to that described in U. S. Patent 1,349,729, August 17, 1920 to E. L. Nelson. It is specifically contemplated that the system of that patent may be used in 50 cooperation with the arrangements herein disclosed in accomplishing the objects of the present invention.

Briefly described, this system is adapted to supply a carrier wave "C" modulated by 55 a current of one frequency "S" to the antenna when the key 6 is open, and to supply a carrier wave "C" modulated by a current of different frequency "S₁" when the key 6 is closed. In both cases the side frequencies and the carrier components are radiated.

At the receiving station R there is shown an antenna circuit 7 inductively coupled to an amplifier 8 for supplying amplified radio frequency waves to a detector 9. The output 60 65 of the detector includes two selective filter

circuits 10 and 11 but obviously any properly designed selective circuits could be used. These selective circuits are designed to be highly selective and are respectively selective of the different modulating currents of frequencies "S" and "S₁." The selective circuits are separately coupled by coils 12 and 13 to the input circuits of balanced detecting or rectifying circuits consisting of devices 14 and 15 and their associated elements. The output circuit of the device 14 includes a winding 16 of a polarized relay and similarly a winding 17 of the polarized relay is included in the output circuit of the device 15.

Polarizing potential is impressed upon 80 the grid or control elements of the devices 14 and 15 by a common source 18 and space current is supplied thereto by the source 19. By maintaining a balanced relation in the 85 circuits of the devices 14 and 15 equal currents will be supplied to the windings 16 and 17.

The armature 20 of the polarized relay is included in a circuit 21 which includes a 90 relay 22. This relay 22 may be an ordinary 90 telegraph sounder or the control winding of any well known marking device.

With the key 6 in the position shown, an unmodulated carrier component of frequency "C" and two side frequencies 95 "C+S" and "C-S" will be supplied to and radiated from the antenna 1. At the receiving station R the incoming unmodulated and modulated components will be amplified by the device 8 and combined in 100 the device 9 to produce a current of the modulating frequency "S." The selective means 10 being resonant to current of the frequency "S," this current will flow through the primary winding of the coil 12. 105 The result of this is that the more strongly the input circuit of the device 14 is excited by the waves impressed upon the secondary winding of the coil 12 the greater will be the average value of space current 110 through the winding 16. The increased current flowing through the device 14 and its output circuit including the winding 16 of the polarized relay actuates the relay armature 20 to open the circuit 21 as shown. 115

When the key 6 engages its contact, a carrier wave modulated by current of frequency "S₁" will be supplied to, and radiated from, the antenna 1. As described above the modulated carrier and side frequency components will be received by the antenna 7, amplified by the amplifier 8, and combined in the detector 9. The resultant current of frequency "S₁" will be selected by the resonant means 11 and supplied to the primary winding of coil 13. The secondary of the coil 13 is connected to the input circuit of the device 15 whereby increased energization of the secondary coil 13 will cause increased space current 130

to flow through the output circuit of the device 15 including the winding 17 of the polarized relay and its armature 20 will be actuated to complete the circuit 21 and energize the winding 22 of the sounder or marking device.

By providing a relay which requires a large current unbalance to move its armature from one position to another, as by 10 using an armature having large inertia, the relay will be more positive in operation and the liability of false signaling will be reduced.

When static discharges of certain frequencies are incident upon the antenna, oscillations may be set up therein, and current will flow simultaneously through both the resonant circuits 10 and 11. Both detectors 14 and 15 will be substantially 20 equally affected, and a substantially equally increased space current will tend to flow simultaneously through the windings 16 and 17.

If the amplitudes of these currents are substantially equal the balanced condition of the detector system will not be disturbed and hence the polarized relay will not operate. Again, if the difference in the amplitudes of the currents flowing through windings 16 and 17 is less than that required to actuate the relay no signaling actuation will result. Thus, by properly designing the receiving circuit, including a balanced detector system adapted to control the flow of 30 currents of large amplitude and utilizing a relay requiring a current of considerable amplitude to actuate its armature, it is possible to provide an arrangement in which the liability of false signaling, due to static 35 discharges, is greatly reduced.

From the preceding description it will be apparent that this invention provides a simple arrangement for radio telegraph signaling in which a carrier wave modulated by two different frequency currents may be used to positively actuate means for identifying marking and spacing signals.

The receiving circuit is herein described as including a high frequency amplifier, 50 but this is not an essential element of the invention.

While a particular arrangement and certain specific details have been described for the purpose of completely and clearly disclosing the nature of the present invention, 55 it is to be understood that this invention is not limited thereto, but only by the scope of the attached claims.

What is claimed is:

1. The method of reducing static disturbance which consists in transmitting a carrier wave modulated by currents of different frequencies, and at a receiving station, detecting incoming signal and static waves to 60 yield the modulating currents and parasitic

currents, separately selecting said modulating currents, utilizing one of said modulating currents to identify marking signals, using the other of said modulating currents to indicate spacing signals, and using the parasitic currents to produce substantially equal and opposing forces tending to produce marking and spacing signals. 70

2. The method of reducing random interference effects which comprises producing 75 a carrier wave alternately modulated at different frequencies, transmitting the unmodulated carrier and the side frequency in both cases, and at a receiving station combining the corresponding components to produce 80 currents of said modulating frequencies, separately selecting said currents, utilizing one of said currents to positively produce marking signals, using the other of said currents to positively produce spacing signals, producing currents by random interference and using said last mentioned currents to tend to simultaneously produce 85 opposing and neutralizing marking and spacing forces. 90

3. In a signaling system means for transmitting in alternation a carrier wave modulated by currents of different frequencies and, at a receiving station, means for producing currents of the modulating frequencies, means for selecting said produced currents, means actuated in one direction by one of said currents to identify marking signals, means actuated in an opposite direction by the other of said currents to identify spacing signals, said two last mentioned means being simultaneously supplied with currents due to random inference such as static discharges. 95

4. In a signaling system means to transmit a carrier wave alternately modulated at different frequencies and, at a receiving station, means for producing currents of the modulating frequencies, means for selecting said currents, a marking circuit, means alternately controlled by one of said modulating currents to positively complete said marking circuit, and by the other of said modulating currents to positively open said marking circuit, said last mentioned means 100 being controlled by currents due to random disturbances such as static discharges in a manner tending to simultaneously energize 105 the circuit opening and closing control means. 110

5. In a signaling system means to transmit a carrier wave alternately modulated at different frequencies and, at a receiving station, means for producing currents of the modulating frequencies, a sounder circuit, 115 a balanced detector, means energized by one of said currents to control one side of said balanced detector to complete said sounder circuit and energized by the other of said currents to control the other side of said de- 120

130

tector to open said sounder circuit, said detectors being jointly controlled by currents due to random disturbances such as static discharges to prevent actuation of the sounder circuit control means.

6. In a signaling system means to transmit a carrier wave alternately modulated at different frequencies and, at a receiving station, means for producing currents of the modulating frequencies, a marking circuit, balanced detectors, a polarized relay having one winding associated with one of the balanced detectors and a second winding associated with the other of said detectors, means

energized by one of said currents for controlling one of said detectors to energize its associated relay winding, means energized by the other of said currents for controlling the other detector to energize its associated relay winding, said means being jointly energized by currents due to random interference to control both detectors, whereby both windings of the relay are jointly energized.

In witness whereof, I hereunto subscribe my name this 27th day of November, A. D. 1923.

HAROLD J. FISHER.
